DEVICE FOR COLLECTING FILAMENTARY MATERIALS

Robert J. Taylor, Claymont, Del., assignor to American Viscose Corporation, Wilmington, Del., a corporation of Delaware

Application April 17, 1943, Serial No. 483,507

9 Claims. (Cl. 18—8)

This invention relates to arrangements for collecting filamentary material and is particularly concerned with the collecting of the filaments while submerged under liquid, such as water.

From any one of various reasons, it may be desired to collect the continuous filaments while still immersed in the spinning liquid either because of incomplete setting up or because of the extreme fineness of the filament diameter. Such filaments are extremely liable to be broken or damaged when passing over guides associated with the collecting or winding mechanism. By collecting them under liquid, the liquid acts as a lubricant and protects the filaments from breakage and severe damage by wear as they pass over the guides associated with the collecting or winding drum. Collecting under liquid may be desirable with filaments and fibers other than freshly spun filaments and fibers. For example, filaments of an extremely abrasive character may be collected under liquid to reduce wear on guides. In addition, filaments and fibers tending to be brittle, such as glass, may preferably be collected under liquid.

Heretofore, traverse guides having filaments guiding channels of relatively short length have been employed in collecting filaments under liquids. Such guides have several disadvantages. One of the most important is the fact that the whipping of the yarn and the turbulence of the liquid which is caused by the reciprocation of the guide within the liquid, and particularly at the ends of the traverse stroke, give rise to a wide variation of tension in the filaments. This variation in tension causes variation in the properties along the length of the filaments. In addition, where extremely fine diameter filaments or filaments which are highly susceptible to breakage are being collected even under liquid, such short length channel guides do not adequately protect the filaments from breakage and excessive wear, especially where high speeds of take-up are involved.

It is an object of this invention to provide an arrangement for collection of filaments under liquids either in the form of a yarn-like bundle of filaments or in the form of a thin sheet-like web of intercrossing filaments in which a novel form of traversing guide is provided which has a long channel length and is mounted in a novel fashion. Other objects and advantages will be apparent from the description hereinafter.

In the drawing, illustrative of the invention,

Figure 1 is an elevation showing the invention applied within a spinning bath,
 Figure 2 shows a modification,
 Figure 3 is a section taken on line III—III of 5 Figure 2,
 Figure 4 is a cross-section taken on lines IV—IV of Figure 2,
 Figure 5 is a cross-section taken on lines V—V of Figure 2,
 Figure 6 is an end view of a modified form of traverse guide,
 Figure 7 is a plan view of another modification of the invention,
 Figure 8 is an elevation of the arrangement of 10 Figure 7,
 Figure 9 is a plan view of a modification; and
 Figure 10 is a vertical section through the embodiment of Figure 9.
 Figure 1 shows the invention as applied to the 15 spinning of filaments and collecting them as a thin sheet-like web of inter-crossed filaments. This arrangement is applicable to filaments with any diameter but is particularly advantageous when applied to the collecting of a wound band 20 of highly intercrossed filaments of extremely small diameters from $\frac{1}{2}$ to 25 microns in diameter, such as disclosed in the application for patent of Robert J. Taylor, Serial Number 479,889, filed March 20, 1943. In Figure 1, there is shown one 25 spinning station of a spinning machine along the length of which a plurality of stations are disposed. This one station or unit comprises a spinneret 2, a traverse guide 3 of tubular shape and a take-up or winding drum or core 4. The spinneret and the traverse guide are submerged 30 in the spinning bath 5 which is disposed in a trough 6 extending the length of the machine. The end of the guide 3 nearest the spinneret may be pivotally mounted at 7 upon a vertical axis within a yoke 8 which depends from and is fixedly secured to a stationary support 9 in the form of a bar or rail extending the length of the machine over the spinning bath. The other end of the tube is supported slidably within a yoke 10 35 depending from the traverse rail 11 which extends along the length of the machine and which is reciprocated lengthwise. In this embodiment, the traverse guide 3 is substantially of the same inside diameter throughout its length and no condensation of the filament bundle occurs except as a result of winding upon the core 4 which causes condensation to a thin web of intercrossed filaments. The swinging of the traverse guide 3 about its pivot substantially at the end nearest 40 the spinneret reduces whipping and turbulence 45

all the way from the open discharge end of the traverse guide back to the spinneret, thus minimizing variation in tension within the filaments spun. The traversing of the filamentary bundle has been found to produce more extensive intercrossing of the filaments, especially of large diameter filaments, as compared to collection without traversing of the filament web or sheet as it approaches the take-up device.

In Figure 2, a modified form of the invention is shown applied to a filamentary bundle obtained from a source of supply other than a spinneret within a spinning bath. In this embodiment, a tow or other bundle of untwisted filaments, preferably continuous, is drawn from a suitable source of supply over the feeding rolls 12 and 12' from which it is directed downwardly to a bath of liquid 13 within a suitable trough 14 or other receptacle. On the way from the delivery rolls 12 and 12' to the bath 13, the filamentary bundle passes over a guide 15 which may be charged electrostatically. Where the filaments are of a hydrophobic character, this guide need not be charged by any extrinsic means as in that case, the guide may be made of a suitable material which tends to develop a static charge upon the filaments as they rub over it. The best material for the guide, in the latter instance, depends upon the particular material of which the filaments are made, glass being highly suitable with such filaments as those of Vynylon (copolymers of vinyl chloride and vinyl acetate). The purpose of this electrostatically charging guide is to cause the filaments to fluff out as a result of electrical repellence. After entering the bath, the filaments pass over the rotatable guide roll 15a through the mouth of a traverse guide 16 whose cross-section varies gradually along its length as illustrated by the cross-sections shown in Figures 3, 4 and 5 in order to condense the bundle to a more or less sheet-like ribbon or web by the time it approaches the winding drum 4 which is operated at the same linear peripheral speed as the delivery rolls 12 and 12'. The entrance end of the guide may be supported for pivotal motion in the same manner as shown in Figure 1. In addition, the entrance may be provided with a flare 17 in this case since the additional turbulence caused by the flare is expended upon completely set filaments and not upon freshly spun filaments as in Figure 1. In Figure 2, the guide rests upon a supporting wall 18 which may extend the length of the bath. The reciprocating motion of the traverse rail 11 is transmitted to the guide 16 by means of a depending forked lever 19 secured to the rail 11 and more particularly shown in Figure 5.

As shown in Figure 2, the traversing guide 16 may be tilted at an angle so that its discharge end extends outside the bath somewhat and the take-up drum 4 may be entirely outside the bath. The traveling filamentary bundle carries sufficient lubricating liquid through the guide 16 to protect the filaments from rubbing against the open end of the guide.

In initially lacing up the device, but slight tension should be applied to the filaments as they are brought to the winding drum 4 so that they are free to fan out in the guide channel 16 and to intercross in haphazard fashion under the influence of the turbulence in the channel 16.

The guide 16 shown in Figure 2 serves to condense the filaments to a sheet-like web and has the advantage of reducing turbulence by presenting a reduced profile to resist the traverse

motion. The guide of Figure 2 may be replaced with a funnel tube of circular cross-section having a substantially continuous reduction in diameter throughout its length where it is desired to condense the filamentary bundle to a yarn-like structure rather than a sheet-like web at the point of winding. The end view of such a guide 20 looking at the small end would be as shown in Figure 6 where the wall 18 and the fork lever 19 for traversing the guide is shown. In this arrangement, the electrostatically charging guide 15 of Figure 2 may be omitted since there is no advantage in fluffing out the filamentary bundle.

15 A modified form of condensing guide is shown in Figures 7 and 8, in which the vertical dimension is first condensed without change of the horizontal dimension of the guide but adjacent the discharge end thereof, the horizontal dimension increases while the vertical dimension continues to decrease, thereby forming a fan-shaped end.

20 Figures 9 and 10 show an embodiment in which the traversing guide 22 first condenses the filamentary bundle in one dimension of its cross-section and subsequently expands the coordinate dimension of its cross-section while continuing to constrict the former dimension. As shown, the cross-section of the bundle is first condensed to a vertical ribbon which subsequently is converted into a substantially horizontal ribbon or web at the point of collection upon the take-up drum.

25 One suitable form of traverse mechanism is shown in Figure 9 in which the traverse rail 11 is provided with a roller 22 which serves as a follower in the groove 23 of the helical cam 24 which may take the form of a drum rotated upon a suitable shaft 25.

30 35 40 While preferred embodiments of the invention have been disclosed, it is to be understood that changes and variations may be made without departing from the spirit and scope of the invention.

45 What I claim is:

1. In apparatus for collecting filamentary material, a container for receiving a body of liquid, means for introducing a filamentary bundle into the liquid in said container, a winding core, a long hollow guide member in said container substantially entirely under the body of liquid therein for conducting the filamentary bundle to the core, said member being pivotally mounted near its entrance end, and means for traversing its discharge end with respect to the core.

2. In apparatus for collecting filamentary material, a container for receiving a body of liquid, means for introducing a filamentary bundle into the liquid, a winding core at least partially immersed in the body of liquid, a long hollow cylindrical guide member substantially entirely under the body of liquid for conducting the filamentary bundle to the core, said member being pivotally mounted near its entrance end, and means for traversing its discharge end with respect to the core.

3. In apparatus for collecting filamentary material, a container for receiving a body of liquid, means for introducing a filamentary bundle into the liquid, a winding core at least partially immersed in the body of liquid, a long hollow condensing guide member substantially entirely under the body of liquid for conducting the filamentary bundle to the core, said member being

pivotedly mounted near its entrance end, and means for traversing its discharge end with respect to the core.

4. In apparatus for collecting filamentary material, a container for receiving a body of liquid, means for introducing a filamentary bundle into the liquid, a winding core at least partially immersed in the body of liquid and rotatable on an axis, a long hollow condensing guide member substantially entirely under the body of liquid for conducting the filamentary bundle to the core, said member being pivotally mounted near its entrance end and having an internal cross-section which gradually changes from a substantially circular section at its entrance end to an opening at its discharge end elongated in a direction generally parallel to the core axis, and means for traversing its discharge end with respect to the core in the general direction of its elongated dimension.

5. In a spinning machine, a container for receiving a liquid spinning bath, a spinneret in the liquid, a winding core, a long hollow guide member substantially entirely under the body of liquid for conducting the filamentary bundle from the spinneret to the core, said member being pivotally mounted near its entrance end, and means for traversing its discharge end with respect to the core.

6. In a spinning machine, a container for receiving a liquid spinning bath, a spinneret in the liquid, a winding core at least partially immersed in the body of liquid, a long hollow cylindrical guide member substantially entirely under the body of liquid for conducting the filamentary bundle from the spinneret to the core, said member being pivotally mounted near its entrance end, and means for traversing its discharge end with respect to the core.

7. In a spinning machine, a container for receiving a liquid spinning bath, a spinneret in the liquid, a winding core at least partially im-

mersed in the body of liquid, a long hollow condensing guide member substantially entirely under the body of liquid for conducting the filamentary bundle from the spinneret to the core, at least one transverse dimension of the internal cross-sectional area of the guide member diminishing in the direction of travel of the bundle therethrough, said member being pivotally mounted near its entrance end, and means for traversing its discharge end with respect to the core.

8. In a spinning machine, a container for receiving a liquid spinning bath, a spinneret in the liquid, a winding core at least partially immersed in the body of liquid and rotatable on an axis, a long hollow condensing guide member substantially entirely under the body of liquid for conducting the filamentary bundle from the spinneret to the core, said member being pivotally mounted at its entrance end and having a tapered cross-section which changes from a substantially circular cross-section at its entrance to an opening at its discharge end elongated in a direction generally parallel to the core axis, and means for traversing its discharge end with respect to the core in the general direction of its elongated dimension.

9. In a spinning machine, a container for receiving a liquid spinning bath, a spinneret in the liquid, a winding core at least partially immersed in the body of liquid, a long hollow guide member substantially entirely under the body of liquid for conducting the filamentary bundle from the spinneret to the core, said member being pivotally mounted near its entrance end and having a cross-section of substantially circular shape throughout its length but decreasing from its entrance end to its discharge end, and means for traversing its discharge end with respect to the core.

ROBERT J. TAYLOR.
